UNITED STATES PATENT OFFICE.

HENRY BIXLER, OF KINNIKINNICK, OHIO.

SAUSAGE-STUFFER.

SPECIFICATION forming part of Letters Patent No. 283,852, dated August 28, 1883.

Application filed December 16, 1882. (No model.)

To all whom it may concern:

Be it known that I, HENRY BIXLER, a citizen of the United States, residing at Kinnikinnick, in the county of Ross and State of Ohio, have invented certain new and useful Improvements in Sausage-Stuffers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention has relation to improvements in sausage-stuffing machines; and it consists in the construction, combination, and arrangement of the several parts, as will be herein-after described, and specifically pointed out in the claims.

20 In the drawings, Figure 1 is a plan view. Fig. 2 is a vertical section on line $x x$, Fig. 1; and Fig. 3 is an end elevation of a machine constructed according to my invention. Figs. 4 and 6 are detail views of the spout; and Fig. 25 5 is a detail view of the movable partition-valve, as will be described.

20 a is the upper and a' the lower boxes of my casing, provided with a suitable bearing, a' , for the shaft of the stuffing-butterfly. These 30 boxes are secured together by bolts b , fastened to bottom box, a' , and extended through brackets b' , secured to upper box, a , and held by nut b^2 . The box a' is provided with a concave bottom, a^3 , which is preferably made of cast-iron, 35 but may be made of any other suitable metal, and the box a' is also provided in its ends with mortises a^4 , which are made in shape of inverted V , and extend from the bearing a^2 to the concave bottom a^3 , as shown in Fig. 2.

40 a^5 is a hole through one end of the box a' , leading into one of the mortises a^4 , as shown in Fig. 2.

45 c is the movable partition-valve, extending from side to side of the box, and having its ends placed in the mortises a^4 , as shown. This valve is placed in the box a' , with its ends arranged within the mortises a^4 . Its upper side is made almost as wide as the portion of the mortises in which its ends rest, while its under side is tapered to a thin edge at the end which is adjacent to and moves over the opening a^5 , and gradually increases in width to

its opposite end, which is of same width as the top of the valve, as shown in Fig. 5. By this construction it will be seen that the 55 movable valve is substantially pivoted or hinged at its upper edge, while its lower edge is free to be moved from side to side over the opening a^5 , forming a vibrating partition, which moves and alternately brings the opening a^5 60 into the right and left portions of the lower box. This valve might be made of same thickness in all its parts; but I prefer the particular shape hereinbefore described, as by such construction much better results are obtained 65 in the stuffing of the sausages.

d is the spout, having the base-plate d' arranged at one end, and the short extension or tube d^2 , which extends within the opening a^5 . The top of the spout d is depressed, as shown 70 in Figs. 3 and 6, and is covered by a cap-piece, d^3 , soldered on either side of the depression, and perforated with a number of holes, as shown. The object of this construction is to provide an air-passage by means of 75 which the air can escape from the intestine as the meat is forced therein, and obviate the picking of the links with needles or other sharp instruments, as is ordinarily done. Thus in forcing the meat into the intestine, the air 80 in the latter will pass into the channel formed by the depressed spout, and escape through the holes of the perforated cap-piece d^3 .

$e e$ are latch-bars pivoted to the side of the casing above and one on either side of the 85 opening a^5 , so that they can be turned down over the base-plate d' , and their ends, when turned down, move into grooves e' , formed in the base-board of the box a' , as shown in Figs. 1 and 3. In securing the spout to the box a' 90 casing the extension d^2 is inserted in the opening a^5 . The base-plate then rests against the side of the box, and the latch-bars are turned down over the same, as shown, locking it firmly in position, and yet so it may easily be 95 removed to be cleansed, or for any other purpose desired.

f designates the main shaft, having the operating-lever f' , and supported in the bearing a^2 .

g is the butterfly or presser, secured on the 100 shaft f , and made of a width equal to the interior width of the boxes $a a'$, and its wings $g' g^2$ are made of a proper length, so their ends will turn flush with the concave bottom a^3 .

The wings of the butterfly or presser are inclined properly from end to end, so that they will conform in shape to the movable partition hereinbefore described. It will be understood 5 that only the side of the wings that engages the partition-valve will be formed to correspond therewith in shape.

In operation, when the several parts are in the position shown in Fig. 2, the meat would 10 be fed in the side marked *x*. The wing *g'* is brought around to bear against the movable partition, and carrying the lower end of the said valve over clear of the stuffing-hole *a'*, and forcing the meat through the said hole 15 into the intestine secured on the spout *d'* to receive it. When this is going on, meat is being placed on the other side, and when all is forced out of the side *x* the lever *f'* is reversed, bringing the wing *g'* to bear against 20 the meat in the opposite side. This operation is repeated, stuffing alternately with the opposite wings of the butterfly or presser.

Having thus described my invention, what I claim, and desire to secure by Letters Patent, 25 is—

1. The combination, with the casing of a sausage-stuffer, of the movable partition, having its upper end substantially pivoted below the butterfly - bearing and its opposite end

movable back and forth over the stuffing-hole, 30 and the butterfly-presser, substantially as and for the purposes set forth.

2. The combination of the sausage-box casing, provided with the opening *a'*, and having the inverted-V-shaped mortises *a'* formed in 35 its opposite ends, the movable partition, having its ends placed in the mortises *a'*, and formed with its end or corner which is adjacent to and moves back and forth over the hole *a'* tapered to an edge, and the butterfly 40 or presser, having the face of its wings formed to coincide with the opposite faces of the partition, substantially as set forth.

3. The combination, with the casing having the opening *a'*, of the spout, constructed with 45 the base-plate *d'* and extension *d'*, arranged to enter the opening *a'*, and the latch-bars, having one of their ends pivoted above and on opposite sides of the opening *a'*, and their opposite ends turned down over the plate *d'* and 50 extended within the grooves *e'*, all arranged substantially as specified.

In testimony whereof I affix my signature in presence of two witnesses.

HENRY BIXLER.
